GAME OR SIMILAR DEVICE

John Dorfman, New York, N. Y., assignor to
Maleo, Inc., New York, N. Y., a corporation of
New York

Application October 21, 1942, Serial No. 462,780

3 Claims. (Cl. 273—135)

This invention relates generally to games and more particularly to such which employ the use of playing cards. More specifically it relates to the combination of playing cards with a game board.

It is an object of the present invention to provide a game in which a game board having a plurality of fixed playing card representations is used with a deck of conventional playing cards, which deck of cards are played on the game board and made to cooperate therewith to form a game similar to the game known as poker.

It is a further object of the present invention to provide a game simulating poker and in which fixed playing members are arranged in predetermined fashion on a game board and a number of individual playing cards are dealt out from the stack of cards and cooperate with the fixed members on the board to produce the game.

It is a still further object of the present invention to provide a game of the above character, wherein advertisements are tied up with the game in such manner as to effectively compel the player to repeat the names of certain brands of products, during the performance of the game.

Yet another object of the present invention is to arrange the fixed playing members on the game board according to established betting odds, preferably in inverse order, that is, a playing member of a lower denomination or value carries betting odds higher than a playing member of a higher denomination or value.

A still further object of the present invention resides in providing each fixed playing member with all four suit symbols of conventional playing cards.

Further objects and advantages of the invention will appear from the following disclosure thereof together with the attached drawings which illustrate a certain form of embodiment thereof. This form is shown for the purpose of illustrating the invention to give satisfactory and reliable results, although it is to be understood that the instrumentalities of which the invention consists can be variously arranged and organized and that the invention is not limited to the precise arrangement and organization of the instrumentalities as herein shown and described.

In the drawings:

Fig. 1 is a plan view of a game board made in accordance with the invention;

Fig. 2 is an enlarged lower left-hand corner of the game board in typical use.

The game board 10 is provided with a plurality of rows of preferably printed fields or boxes

11 and preferably larger adjoining sections or boxes 12. Fields 11 are imprinted with or otherwise carry indicia, emblems or symbols 13, 14, 15 and 16 indicative of suits of playing cards, such as, for example, hearts, clubs, spades and diamonds, respectively and the rows of fields are arranged in spaced parallel relation. The total number of the fields 11 is thirteen to include all of the fifty-two cards of a conventional deck of playing cards from ace to king, inclusive.

In addition to the aforesaid indicia or symbols, the boxes 11 carry respectively indicia, such as, A (ace); K (king); Q (queen); J (jack); etc., and may carry betting odds characters or numbers, preferably consecutively from 3 to 1 to 15 to 1, inclusive.

These fields or boxes 11 may also carry the brand or trade-mark 18 of the advertiser, the advertiser's name 19 or the name 20 of the advertised merchandise.

The larger spaces 12 may be utilized for carrying illustrations 21 of the merchandise.

In the particular embodiment illustrated in Figure 1, the fixed playing members are arranged in a predetermined order, starting with the ace followed by the king, queen, etc., and terminating with the deuce. This is one typical arrangement for this game, it being evident that other arrangements are contemplated within the scope of the invention.

Figure 2 shows three typically played hands. Of course, it is understood that thirteen or less played hands may be exposed on the game board. If all thirteen hands are played, then the entire deck of fifty-two conventional playing cards is used up.

In the instance illustrated in Figure 2, twelve cards of the conventional playing deck are exposed, namely, adjacent the 10 spot playing member 40 as printed on the game board are positioned four cards, namely, two 10's represented by the letter b and two 5's represented by the letter c. Adjacent the 7 spot playing member d printed on the game board are positioned four cards, namely, three cards bearing queens and represented by the letter e and an ace represented by the letter f. Adjacent the 4 spot playing member g printed on the game board are positioned four cards, namely, a 3 spot card b, a deuce i and two aces k. According to the rules of poker, the highest hand on the game board is the one having three tens and two fives (full house), the next to the highest hand is the one having three queens and the lowest hand is the one having two aces.

Referring to Figure 1, it will be seen that ac-

cording to the odds indicia appearing on the game board within the playing member *d*, that this high hand would pay 7 to 1.

Since each of the playing members printed on the game board bears the symbols of all four suits, therefore, in the event that during the course of the game, four individual playing cards having the same suit symbol chance to be positioned adjacent the playing member printed on the game board, then a five-card flush would be presented and if the said playing member and the said four cards indicate a straight, then a straight flush would be presented.

As is evident from what has been heretofore stated, the game follows the rules of poker. The players select their respective playing members on the game board with which they desire to start. This selection would in a measure depend both upon the odds depicted on the playing member and the value indicated thereon; in the embodiment illustrated in the drawings, the lesser the value, the greater the odds.

The deck of fifty-two cards are shuffled, and the dealer successively places a card (face-up) adjacent each of the playing members, in the order in which they appear on the top of the stack of cards as he deals them out. In the example illustrated in Figure 2, these cards are in the following order ten of spades, queen of diamonds, three of diamonds, ten of diamonds, queen of hearts, deuce of spades, five of diamonds, queen of hearts, ace of spades, five of diamonds, ace of hearts, and ace of diamonds.

In this game it is possible to get five of a kind—which beats four of a kind, but does not beat a straight flush or a royal flush. A full house, straight or flush counts in this game the same as regular poker. These hands beat the same hands as in regular poker. As stated heretofore, the printed card on the game board counts as part of both straights and flushes. However, in the case of flushes, the printed member or card on the game board preferably counts only as a part of a flush if the hand does not contain another card of the same denomination as the printed member or card on the game board. In other words, if the ace of spades out of the deck of cards is dealt to the ace on the game board, it makes a pair of aces and does not count as part of a spade flush.

This game is not only extremely interesting, but finds excellent use as an advertising medium. For example, the fixed playing members on the board may be called or designated by certain well-known brands or trade-marks. Referring to Figure 1, one player may select as his play "John Doe" on which the betting odds are 4 to 1; another player may select "Richard Roe" on which the betting odds are 7 to 1, etc.

It is evident that in addition to the game board, only the conventional deck of 52 playing cards are necessary to start playing the game, and any number of players may join the game.

An interesting adaptation of the game is its use to simulate horse racing. Each box *II* printed on the game board with card corners, such as, *a*, *d*, *g*, etc. (Fig. 2) represents an additional card in the deck being used and also represents a "horse" in a race. The cards are laid out alongside of these boxes, as they are dealt off the deck.

All of the thirteen "horses" run in every race whether backed by players or not. Odds against each horse are printed in box *II* and must be adhered to. One player acts as "banker" for three or five races, as agreed upon before the game.

starts, then passes the "bank" on to the next player. In this manner each player, in his turn, has the option to act as "banker." While the banker is shuffling the cards before each race, the players back their choice by placing chips, or tokens, on the printed card, or cards *II* of their choice. When all players have selected their choice, the banker starts the race by dealing out the cards one at a time and places them, in the same rotation as they come off the deck, in the space provided alongside of each printed card on the game board. (Example)—players place their chips or tokens in the boxes with the printed "card corners." The first card dealt off the deck by the banker is placed alongside of the ace printed on the game board, the second card dealt is placed alongside of the king, the third alongside of the queen, and so forth down to the deuce (2). When thirteen cards have been dealt out in this manner—and each card printed on the game board has a card off the deck alongside of it—the same operation is repeated until the banker has dealt out the entire deck of 52 cards. When each printed card on the game board has four cards out of the deck alongside of it—the race is over. The winner of the race is the "Highest poker hand." The banker pays the player or players who selected the winner, the odds indicated on the printed card and, of course, keeps everything placed on losing horses. When the first race is over another is started and, so on, the game continues. This race may be considered a one-mile race. When all the cards printed on the game board have been dealt a first card out of the deck, it compares with the finish of the quarter mile in a horse race, the second card compares with the finish of the half mile, the third card with the finish of the three-quarters—the fourth and last card with the stretch and winner. The banker, or one of the players, can add much hilarity to the party by calling out the running of the race as the cards are being dealt.

The following rules may be observed. Players may back as many horses as they choose in every race. Any number of players may choose and back the same horse, or horses. However, the banker may limit the amount any one player, or all players combined, may place on any horse. All choices must be made before a race starts—no play may be made while a race is in progress. Odds against horses are to win only—there are no place (second) or show (third) odds. The printed card on the game board counts as part of every poker hand.

All "horses" do not have to be played in order to start a race, but, every "horse" runs in the race whether played or not, "horses" not played, run for the banker—who does not pay anyone and takes all should any unplayed "horse" win. In case of a tie (dead heat), the banker pays both winners one-half ($\frac{1}{2}$) of the amount that would ordinarily be paid if the horse won by itself. (Example)—if the ace were in a dead heat, the player would get back only two (2) chips—including his own chip played on the ace. Cards must be dealt out in the rotation specified in above instructions. Mutuals may be played by fixing the same value for every chip, or token, in the game and by dividing the chips, or tokens, played on losing horses, evenly between the chips, or tokens, played on the winner. If the "winning horse" should be one on which no play was made, all losses go into a "jack-pot purse" which is added to the winner's purse of the next race.

As a further adaptation of this game, each winner may be credited with the number of points designated on the box 11. For example, referring to Figure 2, the winner which would be the player who selected the box having the full house would be credited with seven points, as the predetermined value odds are seven to one. A maximum number of points may be fixed for a prize, such as, for example, one hundred points, five hundred points, etc.; as determined by the group of players. Then the first player receiving this maximum score of points would be the winner and receive the prize.

It will thus be seen that there has been provided by this invention a game in which the various objects hereinabove set forth, together with many advantages, are successfully achieved.

The features of novelty which I believe to be characteristic of my invention are set forth with particularity in the appended claims. My invention itself, however, both as to its fundamental principles and as to its particular embodiments, will best be understood by reference to the specification, in which I have described, by way of example only, and not in limitation, certain ways in which my invention may be practiced.

Having thus described the invention, what is claimed as new and desired to be secured by Letters Patent, is:

1. In a game device wherein conventional playing cards are employed; a game board comprising a plurality of rows of fields, said rows being arranged on said board in spaced and parallel relation, four emblems carried by each of

- said fields and representing the four suits of said playing cards, indicia disposed on each of said fields and indicating a value corresponding to a respective value of said playing cards, and a plurality of rows of sections respectively arranged adjacent said rows of fields, at least some of said section rows being positioned intermediate some of said field rows, each of said sections being adapted to support a plurality of 5 said playing cards, the indicia and emblems on each of said fields being adapted respectively for coordination with values and suits of playing cards when positioned on said sections respectively to thereby simulate hands of the game on 10 said board.
2. In a game device wherein conventional playing cards are employed; a game board comprising a plurality of rows of fields, said rows being arranged on said board in spaced and parallel relation, emblems carried by each of said fields and 15 representing suits of said playing cards, indicia disposed on each of said fields and indicating a value corresponding to a respective value of said playing cards, and a plurality of rows of sections 20 respectively arranged adjacent said rows of fields, each of said sections being adapted to support a plurality of said playing cards, the indicia and emblems on each of said fields being adapted respectively for coordination with values and 25 suits of playing cards when positioned on said sections respectively to thereby simulate hands 30 of the game on said board.

JOHN DORFMAN.
